CLARENCE D. PLATT, OF BRIDGEPORT, CONNECTICUT.

SNAP-SWITCH.

1,193,606.

Specification of Letters Patent. Patented Aug. 8, 1916.

Application filed September 10, 1915. Serial No. 49,959.

To all whom it may concern:

Be it known that I, CLARENCE D. PLATT, a citizen of the United States of America, residing at Bridgeport, Connecticut, have 5 invented a new and useful Snap-Switch, of which the following is a specification.

My present invention has for its object to provide an electric switch of improved construction having a high current carrying 10 capacity and a quick snap action of the switch parts.

Other and more specific objects are to simplify and reduce the number of parts, to facilitate assemblage and to decrease the 15 cost of production.

In the accomplishment of these objects, I employ a pivotally supported operating lever and a contact-making lever pivoted to said switch operating lever, said contact-making lever being operated by a spring which serves to impart a snap movement thereto and said switch operating lever being actuated by a suitable push button. The switch operating lever is pivoted on a supporting bracket and a special feature consists in providing this bracket with stops for limiting the rocking or swinging movement of the switch operating and contact-making levers.

30 Various other features and the details of construction will appear as the specification proceeds.

In the accompanying drawing I have shown several preferred embodiments of 35 my invention but it will be understood that I do not intend the claims to be limited to the specific construction shown and described.

In the drawing—Figure 1, is a plan view 40 of a wall switch constructed in accordance with and embodying the invention, the supporting bar and the cover being removed for the purpose of showing the interior parts more clearly. Fig. 2, is a plan view 45 of the cover for the switch parts. Fig. 3, is a sectional view of the switch taken substantially on the plane of the line 3—3 of Fig. 1. Fig. 4, is a similar view taken substantially on the plane of the line 4—4 of 50 Fig. 1. Fig. 5 is a drop perspective view of the several parts of the switch mechanism. Fig. 6, is a fragmentary and more or less diagrammatic view illustrating the invention applied to a pendant switch.

55 In the wall type of switch illustrated the insulating base 7 is in the form of a hollow

box which incloses the switch parts and is supported in proper position by means of a supporting bar or yoke 8 which is secured across the open front end of the hollow base 60 by screws 9.

The switch mechanism consists of but three main parts, a supporting bracket 11, a rocking switch operating lever 12 pivoted therein and a swinging contact-making lever 65 13 pivoted to the switch operating lever. Preferably all these parts are struck up out of blank sheet metal and are therefore inexpensive and easy to produce.

The supporting bracket, in the preferred 70 construction consists of a metal plate having attaching lugs 14 at opposite ends thereof, oppositely disposed pivot lugs 15 intermediate the end attaching lugs and stop bars 16 and 17 at opposite sides of the pivotal axis 75 of the pivot lugs carried by dependent side arms 18. This supporting bracket rests on shoulders 20 on the opposite side walls of the base, and screws 21 passed up through the bottom of the base into engagement with 80 the attaching lugs 14 serve to secure the support firmly in place.

The switch operating lever, designated 12, consists in the present instance of a piece of sheet metal bent to provide spaced apart side 85 portions 26 and oppositely extending arms 27 and 28 projecting laterally from the central plane of the lever. The lever is pivotally supported by a pin 29 passed through openings 30 in the pivot lugs 15 and through 90 pivot openings 31 in the side portions of the lever which are engaged between the pivot lugs. The oppositely extending arms 27 and 28 of the switch operating lever are disposed above the stop bars 16 and 17 and the 95 rocking movement of this lever is thereby limited by the engagement of these arms with the upper edges of the stop bars.

In the wall type of switch shown the switch operating lever is actuated by push 100 buttons 33 and 34 working in openings 35 in the supporting yoke and provided with shanks 36 having hooks 37 engaged with the bearing openings 38 in the ends of the arms 27 and 28.

105 The contact-making lever 13 in the preferred embodiment is made up of a strip of sheet metal bent into substantially U-form to provide spaced apart parallel side portions 41 which are pivotally engaged with 110 the dependent side portions 26 of the switch operating lever. The pivotal engagement of

these parts is effected in the present disclosure by providing angularly projecting lugs 42 on the upper end of the arms 41 which engage in bearing openings 43 in the lower ends of the side portions 26. One of the bearing openings 43 is shown provided with an entrance slot 44 opening thereto to admit one of the lugs 42 after the other lug 42 has been engaged in the other bearing opening. The contact-making lever co-operates with suitable contact devices, said devices consisting in the present disclosure of two relatively spaced apart contacts 45 which are bridged by the contact-making lever.

15 The snap action is secured by a spring 47 having its lower end engaged with a loop 48 formed on the lower or free end of the contact-making lever and its upper end anchored at a point above the pivotal connection between the two levers. In the illustration the upper end of the spring is hooked over the pivot pin 29. This spring, thus connected constitutes the two levers of a spring toggle as will be evident from Fig. 3.

20 25 The contact-making lever, swinging as it does below the stop bars 16 and 17, is limited in its movement by engagement with the lower edges of these stop bars.

30 The operation will be clear from the foregoing. When the push button 33 in Fig. 3 for instance, is depressed the switch operating lever will be rocked to straighten out the toggle constituted by the two lever members and as soon as the central point is reached the spring will act to throw the contact-making lever over toward the left with a quick snap movement and into forcible engagement with the relatively stationary contacts. When the other switch button is depressed an opposite movement will be effected and the circuit will be broken with a quick movement. It will be noted that in breaking the circuit the spreading action of the toggle will have the effect of causing the contact-making lever to slide over the surface of the contact and thereby wipe the contact free of any foreign matter. In this sliding action the contact has a compound movement embodying first a comparatively straight forward or outward movement and then a partial rotary movement which tends to free the contact lever of the stationary contacts and give it a start on its swinging movement. This is due to the fact that as the operating lever rocks on its pivot, the pivotal connection between the two levers swings in a circular path, first forcing the contact-making lever outward, causing it to slide over the stop bar and then rocking the lever on the stop bar as a fulcrum. As the lever fulcrums on the stop bar the contact end of the lever swings in a substantially circular path tending to free it of the contacts and to give it a start preliminary to the snap movement given it by the spring.

The switch parts are preferably protected by a cover 50 closing the open end of the hollow switch base and held in place in the illustration by being seated on a shoulder 51 on the base beneath the supporting bar 8. 70 This cover is provided with opening 52 for the push buttons.

It will be evident that the invention may be embodied in different kinds of switches. In Fig. 6 for instance the switch movement 75 is shown applied to a pendant type of switch. Here the support is designated 55, the oscillating switch lever 56, and the contact-making lever 57, the parts operating as before described, except that in this case the switch operating lever is provided with a projecting lug 58 at the center thereof which engages at 59 with a double-ended push button 60 extending through the shell 61 of the switch.

85 What I claim is:—

1. In a quick throw switch, an insulating base, a support mounted on said insulating base, a rocking switch operating lever pivoted on said support having side arms extending in opposite directions from the point of pivotal support and angularly extending arms dependent from the point of pivotal support, stops carried by the support on opposite sides of the pivotal center of the operating lever and disposed beneath the side arms of said operating lever to be engaged thereby and limit the throw of said operating lever, a contact making lever pivoted to the dependent arms of the switch operating lever and swinging to opposite sides into engagement with the stops on the support, a spring connected on its lower end to the free end of the contact making lever and anchored on its upper end at a point above the pivotal connections between the levers and push buttons connected to the respective side arms of the switch operating lever.

2. In a quick throw switch, a support having pivot lugs and spaced apart stop bars disposed at opposite sides of the pivotal axis of said lugs, a rocking switch-operating lever pivoted on said lugs and limited in its rocking movements by engagement with the upper sides of said stop bars, a dependent contact-making lever pivoted to said switch-operating lever below the pivotal support of said switch-operating lever and limited in its swinging movements by engagement with the under sides of the stop bars and a spring connection between the free lower end of the swinging contact-making lever and a point above the connection between the two levers to thereby constitute said two levers 125 a spring toggle.

3. In a quick throw switch, a support having attaching lugs at the ends thereof, spaced upstanding pivot lugs between the attaching lugs and dependent arms at oppo- 130

- site sides of the pivot lugs carrying stop bars, a rocking switch-operating lever pivotally supported between the pivot lugs and limited in its rocking movements by engagement with the upper sides of said stop bars, a dependent contact-making lever pivoted to said switch-operating lever below the pivotal support of said switch-operating lever and limited in its swinging movements by engagement with the under sides of the stop bars and a spring connection between the free lower end of the swinging contact-making lever and a point above the connection between the two levers to thereby constitute said two levers a spring toggle. 15
4. In a quick throw switch, a support having spaced apart pivot lugs and spaced stop bars disposed at opposite sides of the pivotal axis of said lugs, a rocking switch-operating lever having spaced side portions pivotally engaged between the spaced pivot lugs and oppositely extending arms engaging the upper sides of the stop bars to limit the rocking movements of said lever, a dependent contact-making lever having spaced sides pivoted to the spaced side portions of the switch-operating lever and a spring connection between the free end of the contact-making lever and a point above the pivotal connection between the two levers. 25
5. In a quick throw switch, a support having spaced apart pivot lugs and spaced stop bars disposed at opposite sides of the
- pivotal axis of said lugs, a rocking switch-operating lever having spaced side portions 35 engaged between the spaced pivot lugs and oppositely extending arms to engage the upper sides of the stop bars, a pivot pin passed through the pivot lugs and the spaced side portions of the switch-operating lever, 40 a dependent contact-making lever having spaced sides pivoted to the spaced side portions of the switch-operating lever and an attachment loop on the lower end thereof and a spring connected to the pivot pin at 45 its upper end and to said attachment loop at its lower end. 45
6. In an electric switch, a support, a switch operating lever pivoted on said support and provided with spaced dependent 50 side portions, a contact-making lever having spaced sides pivotally engaged with the side portions of the switch operating lever, one of said levers having bearing openings in the side portions thereof and the other of 55 said levers having angularly projecting lugs for engagement in said bearing openings, one of said bearing openings having an entrance slot cut thereinto from the edge of the member in which it is formed to receive 60 the angular lug on the other member, and a spring connection between the free end of the contact-making lever and a point above the pivotal connection between the two levers. 60
